(57) **CLAIM**

The ornamental design for a blender, as shown and described.

DESCRIPTION

FIG. 1 is a top front perspective view of a blender according to one exemplary embodiment of the present design.

FIG. 2 is a front view of the blender of FIG. 1 with a vessel portion separated from a base portion.

FIG. 3 is a front view of the blender of FIG. 1.

FIG. 4 is a back view of the blender of FIG. 1.

FIG. 5 is a left side view of the blender of FIG. 1.

FIG. 6 is a right side view of the blender of FIG. 1.

FIG. 7 is a top view of the blender of FIG. 1.

FIG. 8 is a bottom view of the blender of FIG. 1; and,

FIG. 9 is a bottom rear perspective view of the blender of FIG. 1.

The broken lines are directed to unclaimed features of the blender and form no part of the claimed design.
